UNITED STATES PATENT OFFICE

JOHN MONACO, OF EAST ORANGE, NEW JERSEY

DESIGN FOR A SIGNAL LIGHT CASING

Application filed June 13, 1932. Serial No. 44,073. Term of patent 14 years.

To all whom it may concern:

Be it known that JOHN MONACO, a citizen of the United States of America, residing at East Orange, in the county of Essex and State of New Jersey, has invented a new, original, and ornamental Design for a Signal Light Casing, of which the following is a specification, reference being had to the accompanying drawing, forming part thereof.

Figure 1 is a front elevation of the signal, and,

Figure 2 is an end view of same.

I claim:

The ornamental design for a signal light casing, as shown.

In testimony whereof I affix my signature.

JOHN MONACO.
